Clayton P. Breining, INVENTOR,

UNITED STATES PATENT OFFICE.

CLAYTON PAUL BREINING, OF MILL HALL, PENNSYLVANIA.

FOUNTAIN-TOOTHBRUSH.

1,340,115.

Specification of Letters Patent. Patented May 11, 1920.

Application filed January 14, 1918. Serial No. 271,049.

To all whom it may concern:

Be it known that I, CLAYTON P. BREINING, a citizen of the United States, residing at Mill Hall, in the county of Clinton and 5 State of Pennsylvania, have invented a new and useful Fountain-Toothbrush, of which the following is a specification.

This invention relates to tooth brushes, and more particularly to fountain tooth 10 brushes which have means for containing a supply of dentifrice which may be fed to the brush proper as needed.

The object is to provide a tooth brush of this class which is adapted to be used in conjunction with a cartridge filled with the dentifrice, and which may be easily applied to the brush, after the preceding cartridge has been emptied and removed therefrom, the 15 said cartridge being manipulated to forcibly 20 eject its contents into the handle of the brush, thereby displacing the dentifrice therein and causing a thin ribbon of the same to be projected through the bristles of the brush to assume a position thereon ready 25 for instant use.

A further object is to provide a brush, especially adapted to traveler's or military use, having a reservoir for containing a large quantity of the dentifrice which may 30 be easily and quickly replenished by the simple application of an additional cartridge, and which is effectually prevented from leakage or from becoming contaminated, the same being contained wholly 35 within the handle and the cartridge comprising a part thereof, and only enough of the same being ejected for immediate use, which enables the brush to be readily washed and kept in sanitary condition without 40 in any way affecting the contents of the reservoir.

A full and complete understanding of the invention may be obtained from a consideration of the following detailed description, 45 taken in connection with the accompanying drawing forming a part of this specification; it being understood that, while the drawing shows a practical form of the invention, the latter is not confined to strict 50 conformity therewith, but may be changed or modified so long as such changes or modifications mark no material departure from the salient features of the invention, as specifically pointed out in the appended claims.

55 In the drawing, in which like reference

characters designate similar parts throughout the several figures:

Figure 1 is a perspective view of a fountain tooth brush constructed in accordance 60 with the present invention;

Fig. 2 is a longitudinal view of the same; Fig. 3 is a detail plan view of the head 65 of the brush and adjacent parts, the bristles being shown in section to expose the outlet orifice for the dentifrice;

Fig. 4 is an elevation of one of the supplemental cartridges used in conjunction with the brush and forming part of the handle thereof, while in use;

Fig. 5 is a longitudinal section of the 70 same; and

Fig. 6 is a detail transverse section taken on the line 6—6 of Fig. 2.

Referring to the drawing, there is illustrated a brush head 1, which is preferably 75 formed of bone, celluloid, or any other of the materials generally used for this purpose, and having the usual bristles 2 mounted therein in the customary manner. The head 1 is provided with a central longitudinal extension or neck 3, preferably formed integral therewith and of somewhat larger diameter than the thickness of the head and provided in its outer end with an interiorly threaded socket 4, the said socket communicating with a central longitudinal counterbore, providing a channel 5 of smaller diameter than said socket and extending to the center of the head 1 and there communicating with an outlet orifice 6, directed 80 toward the bristles and located centrally thereof. The channel 5 may be round in cross sectional area to render the same easily produced, while the orifice 6 is preferably 85 in the form of a narrow slit, rectangular in cross sectional area and arranged transversely of the head 1, one or more tufts of the bristles 2 being omitted at the center of the head in order to form an open space 7 90 for the passage of a thin ribbon of dentifrice which will be emitted from the orifice upon the manipulation of certain parts to be described. The space 7 will allow the said ribbon to reach the active ends of the bristles without being broken and to bend 95 or flex in one direction, or the other to lie flat upon the said active ends of the bristles, thus assuming the most advantageous position on the brush for immediate action upon the teeth when first applying the brush 100

110

thereto, in the same manner as when a ribbon of tooth paste is applied from an ordinary tube upon an ordinary brush in a well-known manner.

5 A hollow handle 8, constituting a reservoir for the dentifrice, is formed of any suitable thin, light metal, preferably round in cross section, and is provided, at one end, with a reduced extension 9, threaded exteriorly and adapted to be screwed into the said socket 4, the internal diameter of said extension being about as much smaller than the internal diameter of the reservoir or handle 8, as it is larger than the diameter 15 of the aforesaid bore or channel 5 formed in the brush head 1. This provides for the gradual reduction in the size of the stream or body of dentifrice being forced through the described parts in a manner to be described, and to cause the same to issue from the orifice 6 in a compact and unbroken ribbon as will be readily understood.

The outer end of the handle or reservoir 8 is provided with a spider 10 comprising 25 an annular ring of a diameter to permit its being forced into the end of the handle and to remain there permanently; it may, however, be necessary to solder or otherwise secure the same in such position. Arms 11, 30 formed integrally with the ring of the spider 10 and providing spaced passageways therebetween, are connected to a centrally located, threaded collar 12 arranged longitudinally of the reservoir and adapted to receive the 35 threaded stem 13 carried by a longitudinally movable shell or casing, constituting a cartridge 14.

The cartridge 14 has an imperforate outer 40 end wall 15, to which the end of the threaded stem 15 is soldered or secured in any other well-known manner, and the exterior, circumferential surface of the cartridge is milled or serrated, as at 16, in order to be readily grasped between the thumb and 45 finger of the operator to turn the same, thus causing the threaded stem 13 to advance through the threaded collar 12 and to draw the said cartridge along with it, the internal diameter of the latter being such as to snugly 50 fit the external diameter of the handle 8, which telescopes into the same and freely communicates with the interior thereof by reason of the passages through the spider 10.

In order to prevent any leakage of the 55 dentifrice from either the handle or the cartridge, for it must be understood that when the brush is bought from the dealer the cartridge is applied and fully extended and both cartridge and hollow handle 60 charged or loaded with the dentifrice; a rubber gasket 17 is located within the inner or open end of the said cartridge, in surrounding relation to the handle, the metal being slightly expanded, as indicated at 18, 65 to form the necessary space for the said

gasket. It will be seen that the gasket 17 effectually prevents any of the contents from escaping when the parts are being telescoped to feed a supply of dentifrice to the brush, and that the gasket 17 will also act 70 to wipe off any of the same which may have adhered to the outer surface of the handle, when the cartridge is unscrewed for removal from the handle, after all the contents of the same have been used. 75

The contents of the cartridge freely mix or intermingle with the contents of the handle, and, upon turning the former to cause the same to advance along the exterior of the handle, the said contents cause a continuous stream or ribbon to be ejected from the orifice, until the cartridge is entirely emptied, when the same may be unscrewed from its engagement and removed therefrom and thrown away when a new, loaded cartridge may be easily applied to the handle of the brush. Such additional cartridges, as illustrated in Figs. 4 and 5 of the drawing, may be carried in reserve, by a person and are supplied with a removable cap 19 80 formed of stamped metal and consisting of an externally milled flanged head 20 adapted to snugly fit around the expanded open end of the cartridge having the rubber gasket 17 therein, and having a centrally-located, 85 internally threaded extension 21 carried by the head and adapted to receive the end of the threaded stem 13 of the cartridge, said stem projecting sufficiently for such engagement. The removable cap 19 is thus held 90 in position upon the open end of the additional cartridges until it is desired to use the same, when said cap may be removed and discarded, and the cartridge applied to the handle of the brush and manipulated in 95 the manner described. A perforated cover, of any desired formation, is indicated at 22 in Fig. 2, and may be applied to the brush to protect the bristles thereof when the brush is not in use. 100

From the foregoing, it will be seen that an extremely simple and cheaply manufactured fountain brush has been provided, which is especially adapted for military or traveler's use, and which has the added advantage of always having an ample supply of the dentifrice ready to be projected onto the bristles, and that the same may be easily replenished without soiling the hands or the brush and without any waste of the dentifrice. 110

What is claimed is:—

1. A fountain brush comprising a bristle carrying head having a channel communicating with the bristles, a tubular handle 115 constituting a reservoir and communicating with said channel, a spider carried by the open outer end of the handle and having a threaded sleeve, and a cartridge comprising a tubular casing of a diameter to per- 120

- mit the said handle to telescope therein, and a threaded stem secured centrally in said casing and extending longitudinally through the cartridge and beyond the open end 5 thereof and adapted to engage the said threaded sleeve of the spider to advance the cartridge along the handle, upon a turning movement of the cartridge.
2. A fountain brush comprising a brush head having bristles and an extension provided with a channel extending to the head, a hollow handle constituting a reservoir connected to the extension and communicating with the channel and provided at its 15 outer open end with a fixed spider having a central threaded orifice, a tubular cartridge closed at its outer end and open at its inner end and having a central, longitudinally disposed threaded stem secured to said 20 closed end and extending to and beyond said open end, said cartridge being adapted to snugly fit around the hollow handle and
- having a rubber gasket interiorly arranged within its open end to hug the said handle, said stem having engagement with the 25 threaded orifice of the spider to advance the cartridge along the handle upon a turning movement of the cartridge.
3. A cartridge for use with a fountain brush, comprising a casing open at one end 30 and permanently closed at the other end, a threaded stem secured to the closed end and extending centrally through the casing beyond the open end thereof, and a removable cap for closing the open end of 35 the casing and covering the extended end of the stem.

In testimony that I claim the foregoing as my own, I have hereto affixed my signature in the presence of two witnesses.

CLAYTON PAUL BREINING.
